United States Patent Office

Des. 180,465
Patented June 18, 1957

180,465

TELEVISION CABINET

Samuel E. Adler, Chicago, Ill.

Application November 14, 1956, Serial No. 43,768

Term of patent 14 years

(Cl. D56—4)

Fig. 1.

Fig. 2.

Fig. 1 is a front perspective of a television cabinet, showing my new design; and

Fig. 2 is an end elevational view, the opposite end to that shown being substantially identical.

The dominant features of my design reside in those portions shown by full lines of the drawing.

I claim:

The ornamental design for a television cabinet, as shown and described.
